UNITED STATES PATENT OFFICE.

MARK E. FERNALD, OF SAUGUS, MASSACHUSETTS, ASSIGNOR TO C. C. BLAKE, INCORPORATED, OF BOSTON, MASSACHUSETTS, A CORPORATION OF NEW YORK.

METHOD OF MAKING CASTING-PATTERNS.

1,266,113.

Specification of Letters Patent.

Patented May 14, 1918.

Application filed October 1, 1915. Serial No. 53,639.

To all whom it may concern:

Be it known that I, MARK E. FERNALD, a citizen of the United States, residing at Saugus, in the county of Essex and State 5 of Massachusetts, have invented a new and useful Improvement in Methods of Making Casting-Patterns, of which the following is a specification.

The present invention relates to methods 10 for making casting patterns and more particularly to a method for making the casting patterns which determine the form of the leaders used in automatic shoe machines and other sole-shaped devices having peripheral flanges thereon such, for instance, 15 as sole cutting dies.

It has been proposed to perform the various operations in the manufacture of shoes automatically. In one system of automatic 20 shoe machines the transfer of the point of operation of the tool along the work is controlled by a leader upon which the work supporting jack is mounted. These leaders usually comprise a body portion having the 25 same form on one face as the sole of the shoe mounted upon the jack, a flange on the edge of the body portion which is usually provided with teeth for engagement with the driving pinion and a bevel formed 30 above the teeth on the exterior face of the flange at the upper side thereof. The flange also acts as a guide for swinging the jack laterally to permit the tool to traverse the reverse curves of the work. One of the prin- 35 cipal objections to the use of these automatic machines is the cost of producing these leaders which vary in size and shape with the various sizes and styles of soles intended to be incorporated into a shoe. As

40 well known to those skilled in the art it is necessary in making a casting pattern to allow for the shrinkage in the casting. Furthermore, in making a leader for a shoe machine it is also necessary to allow for 45 the "spring" of the last upon which the sole to be incorporated into the shoe is secured. The principal reason for the high cost of these leaders is that heretofore it has been necessary to employ a skilled pattern 50 maker in order to produce a leader casting pattern having the metal shrinkage and the "spring" of the last measurements incorporated therein.

The object of the present invention is to 55 provide a simple, cheap and effective method

by means of which the casting patterns which determine the form of the leaders employed in automatic shoe machines may be manufactured without the aid of a pattern maker or other skilled labor.

60

To the accomplishment of this object and the production of a novel casting pattern the features of the invention relate to certain methods, devices, combinations and arrangements of parts hereinafter described 65 and then set forth broadly and in detail in the appended claims which possess advantages readily apparent to those skilled in the art.

The various features of the present in- 70 vention will be readily understood from an inspection of the accompanying drawings showing the best method of practising the invention at present known to the inventor, in which,

75

Figure 1 is a front elevation of a machine for winding paper about the edge of a sole-shaped blank to build a flange thereon;

Fig. 2 is a sectional elevation of the casting pattern after being operated upon by 80 the winding machine;

Fig. 3 is an elevation, partly in section, of a machine for imparting a draft to the flange of the casting pattern;

Fig. 4 is an elevation, partly in section, 85 of a machine for beveling the exterior face of the flange at the upper end thereof;

Fig. 5 is a plan of the finished casting pattern; and

Fig. 6 is a sectional elevation of the fin- 90 ished casting pattern.

Describing now in general terms my novel method of making casting patterns which determine the form of the leaders employed in automatic shoe machines, the first step 95 consists in the production of the flat blank for the foundation of the pattern. The flat sole-shaped blank having the shrinkage of cast iron and the "spring" of the last measurements incorporated therein may be pro- 100 duced by projecting the edge of a sole on the last upon a plane and then enlarging the area thus produced by the amount of the shrinkage of the metal used for casting the leader. Preferably I produce the blank by 105 means of the geometrical instrument disclosed in application for Letters Patent of the United States filed by me March 22, 1915, Serial No. 16,049. In this machine a feeler travels around the peripheral edge 110

of the sole on the last. The feeler is operatively connected to a pencil arranged to travel over a plane surface and record the movement of the feeler thereon. The connections between the pencil and feeler are such that the rising and falling movements of the feeler in traveling up and down the various slopes on the sole are not transmitted to the pencil. The movements which are imparted to the pencil by the feeler are enlarged by the shrinkage of the metal used in casting the leader. As well known to those skilled in the art it is necessary in making a casting pattern to allow for shrinkage in the casting. Furthermore, in making a leader for a shoe machine it is necessary to allow for the "spring" of the last upon which the sole to be incorporated into a shoe is secured. By this means a sole-shaped area is traced having the shrinkage of cast iron and the "spring" of the last incorporated therein. With this sole-shaped area as a guide a flat blank is made having the same size and shape. This sole-shaped blank is then inserted into the machine described in application for Letters Patent of the United States filed by me October 27, 1914, Serial No. 868,921. This machine is provided with a rotatable support for the blank; devices for supporting, guiding and feeding a strip of material, such as paper; and a pair of rolls for attaching the paper to the peripheral edge of the blank and winding the paper in layers thereon. To build the guiding flange the rolls are mounted upon a carrier which tips automatically as the point of operation of the rolls is transferred around the reverse curves of the blank to maintain the rolls substantially normal to the point of operation. This carrier is mounted on a swinging support which swings automatically during the rotation of the blank to permit the rolls to travel around the toe and heel portions of the blank and reach the shank portions thereof. The machine is also provided with a feed accelerator which imparts an automatic pull to the supply end of the paper so that the paper may be attached to the shank portions of the blank while the paper is free from tension. After the pattern is completed by this machine the draft necessary for the removal of the pattern from the sand is imparted to the pattern by a second machine which is disclosed in application for Letters Patent of the United States filed by Charles C. Blake, October 29, 1914, Serial No. 869,336, to which reference is made by permission. This machine is provided with a series of rolls which simultaneously support, guide, feed and operate automatically upon the pattern to impart the draft thereto and remove any roughness on the top and bottom faces of the flange. The pattern upon its removal from this machine is dried and is

then inserted into the machine described in application for Letters Patent of the United States filed by Charles C. Blake, September 18, 1915, Serial No. 51,450, to which reference is made by permission. This machine is provided with a beveling knife and devices for supporting, guiding and feeding the pattern to transfer the point of operation of the beveling knife around the flange and form a bevel in the exterior face of the flange at the upper end thereof. The pattern is then provided with a coat of shellac.

Referring now to the drawings the sole-shaped blank 1, of wood or paper or fiber material, having the metal shrinkage and the "spring" of the last measurements incorporated therein is secured to a clamp 2 which is rotated in a clockwise direction continuously during the operation of the machine through gears 3 and 4 which are driven from some suitable source of power from a driving shaft 5. Before the blank is rotated one end of a strip of tacky paper is attached to the edge of the blank. A pair of tools is then brought down upon the attached paper one of which guides or lays the paper in position upon the edge of the blank during the rotation thereof and the other one of which fixes or sets the tacky paper in a permanent position. The paper-laying tool comprises a flanged roll 6 which is journaled in a roll carrier 7 centrally pivoted on a stud bolt 8 secured to a supporting arm 9 which is pivoted at 10 on the machine frame. The roll carrier 7 also carries the fixing tool which comprises a roll 11. The rolls are normally held away from the blank to permit the initial attachment of the paper thereto by a spring-actuated pivoted dog 12 carried by the arm 9 and arranged to engage a lug 13 carried by a curved guide 14 the arms of which loosely embrace the arm 9.

The paper for the blank may be presented thereto in any suitable manner found desirable or expedient. In the machine illustrated in the drawings the strip of paper, provided on one face with a normally non-adhesive coating, is carried on a roll 15 the usual wooden core of which rotates freely on the hub of a stationary reel 16. The strip of paper from the roll is led through an opening (not shown) in the machine frame, over an abutment 17 formed on the cover of a water tank 18, and then over a roll 19 arranged to rotate partially within the water tank. In order to render the coated face of the paper tacky the roll 19 is provided with a felt rim 20 which, as it passes beneath the surface 21 of the water in the tank 18, becomes saturated with sufficient moisture to thoroughly wet the coated face of the paper when the paper is pressed against the felt rim. The paper is pressed against the felt rim 20 by a second roll 22 mounted on a

shaft 23 journaled in the legs of a bifurcated arm 24 which is pivoted at 25 on the machine frame. A finger 26 depending from the arm 24 insures the contact of a substantial length of paper with the roll 19. The roll 22 is normally pressed against the paper on the roll 19 by a coiled spring 27 one end of which is connected with the arm 24 and the other end of which is connected to the machine frame. The shaft of the rolls 19 and 22 carry gears 28 and 29, respectively, normally intermeshed so that as the paper is fed by the rotation of the blank to which it is attached the rolls will rotate together.

15 In order to separate the rolls, when the operating tools are held out of their operating position, so as to permit the ready introduction of the paper between them the arm 9 carries a pin 30 which, as the arm is being elevated to latch the dog 12 on the lug 13, contacts with an extension 31 of one of the legs of the bifurcated arm 24 thereby separating the rolls 19 and 22 and disconnecting the gears 28 and 29.

25 After the paper has been rendered tacky by the moistening apparatus the paper is led over the roll 22 to bring its tacky face uppermost and is then led over a roll 32 and between a pair of pins 33 mounted on a plate 34. The plate 34 normally rests at one end upon a pin 35 carried by the arm 9 and its other end is bifurcated so that it may straddle the roll 11 and rest upon the upper face of the roll carrier 7. Connected to the rear 30 of the arm of the bifurcated plate 34 is a pair of lugs 36 by means of which the plate 34 is pivoted upon the stud bolt 8. The paper is then led between the roll 6 and a bridge 37 on the roll carrier 7 to the point 35 of operation at which one end of the tacky paper is attached to the blank.

After one end of the paper has been initially attached to the edge of the blank and the operating tools depressed to engage 40 the attached paper the machine is thrown into operation to rotate the blank to transfer the point of operation of the tools around the blank to draw an additional supply of paper from the roll 15. During the transfer of the point of operation of the tools around the blank the roll carrier 7 automatically tips on the bolt 8 to maintain the tools substantially normal to the point of operation as illustrated in Fig. 1. As the blank 45 being operated upon is sole-shaped, there is a tendency for the paper to "drum head" across the shank portion of the blank owing to the tension placed upon the paper by the rotation of the blank. To overcome this 50 tendency the roll carrier 7 as it tips to maintain the roll substantial to the point of operation of the toe and heel portions of the blank actuates the plate 34 to pull upon the supply end of the paper so as to produce 55 slack in the paper as illustrated in Fig. 1

and thus enable the rolls to attach the paper to the shank portion of the blank while the paper is free from tension. The plate 34 returns under the influence of gravity to its original position as soon as the carrier tips 70 in the opposite direction during the transfer of the rolls along the shank portion of the blank. The plate 34 is herein called a feed accelerator as it accelerates the feed of the strip due to the rotation of the blank during 75 the transfer of the point of operation of the tools around the blank. The arm 9 which supports the roll carrier 7 swings on its pivot 10 to permit the rolls to travel around the ends of the blank and reach the shank 80 portion thereof. As illustrated in Fig. 1 the axis of the rotating blank 1 and the axis of the carrier 7 are located at equal distances from the axis of the support 10. This construction permits the rise and fall of the 85 rolls 6 and 11 under the influence of the rotating blank without danger of binding or producing excessive pressure as they reach the toe and heel portions of the blank. It will also be seen from an inspection of 90 Fig. 1 that the journal for the roll 6 is located at a greater distance from the axis of the carrier 7 than the journal for the roll 11. By locating the journals for the rolls 6 and 11 at different distances from the axis 95 of the tipping carrier in the manner described most of the weight of the arm 9 and its supporting parts is transmitted through the roll 11 to the work. This manner of mounting the rolls 6 and 11 insures the operation of the roll 6 under a light pressure to 100 lay the paper in position and the operation of the roll 11 under a heavy pressure to fix the paper laid by the roll 6.

The blank is rotated until a flange of the 105 desired thickness is built upon the edge thereof at which time the supply end of the strip of paper is severed and the pattern removed from the machine. This pattern is illustrated somewhat exaggerated in section in Fig. 2. As shown it consists of a body portion 38 comprising the sole-shaped blank and a laminated flange 39 which has been built upon the blank by winding the strip of paper in layers around the peripheral edge of the blank.

In order to impart the draft to the flange and smooth the irregularities on the top and bottom faces of the flange the pattern is passed through a machine provided with 110 a series of rolls which support, guide, feed and operate automatically upon the pattern as it passes through the machine. As shown in Fig. 3 these rolls comprise a pair of rolls 40 and 41 which engage the top and bottom 115 faces of the body portion of the pattern, respectively, and which are also constructed and arranged to engage the inner faces of the flange and impart the draft thereto, a pair of rolls 42 and 43 which engage the 120

125 faces of the flange portion of the pattern, respectively, and which are also constructed and arranged to engage the outer faces of the flange and impart the draft thereto, a pair of rolls 44 and 45 which engage the 130

top and bottom faces of the flange, respectively, and smooth the irregularities thereon, and a fifth roll 44 which engages the outer face of the flange and imparts the draft thereto.

After the draft has been imparted to the pattern the pattern is first dried and then inserted into a machine which removes the surplus stock from the exterior face of the pattern at the upper side thereof in order that the leader made from the pattern may be provided with a bevel on the upper side of the exterior face of the guiding flange. In this machine the pattern is supported upon a platen 45 and the pattern is fed over this platen by a pair of feed rolls 46 and 47 which engage respectively the inner and outer faces of the flange. The feed rolls 46 and 47 are substantially frusto-conical in shape in accordance with the shape of the draft in the flange. With this construction the rotation of the rolls 46 and 47 feeds the pattern over the platen and also swings the pattern during the feed to maintain the reversely curved portions of the flange in proximity to the operating point in the line of feed. The roll 47 is dished upon its upper face 48 to permit the operation of a rotary bell-shaped cutter 49 close to the roll. By employing a bell-shaped cutter and a feed roll having its upper face dished on a curve concentric to the cutting edge of the knife a bevel 50 will be formed on the exterior face of the flange at the upper end thereof. The cutter rotates in a counter-clockwise direction in order to form a clean cut on the flange. By rotating the cutter in this direction there is a tendency for the cutter to lift the pattern from its support. To overcome this tendency a presser foot 51 is provided which engages the top face of the flange close to the operating point. The foot 51 is carried upon a guard 52 which covers the cutter 49. After the pattern is provided with the bevel 50 a fillet of beeswax 53 is placed in the angle at the juncture of the flange 39 and body portion 38 (Fig. 6) in order to prevent the molder's sand from lodging in the cracks at these points. The pattern is then finished by providing it with a coat of shellac.

While the illustrated embodiment of the present invention is directed to a method for use in making casting patterns for shoe machine leaders and for sole cutting dies it will be apparent to those skilled in the art that the methods herein disclosed may be advantageously employed in making other kinds of flanged casting patterns.

The operations which are performed as above described and illustrated are those which are preferred in practising the pres-

ent invention. It is to be understood, however, that except as defined in the claims the invention is not limited to the precise methods illustrated and described and that the steps of the methods may be varied or modified without departing from the spirit of the invention.

What is claimed as new, is:—

1. That improvement in the art of making patterns for casting the leaders used in automatic shoe machines which consists in forming a suitable blank having the shrinkage of a casting and the spring of a last measurements incorporated therein, attaching a strip of material to the edge of the blank to form a flange thereon, and imparting a draft to the flange, substantially as described. 70

2. That improvement in the art of making patterns for casting the leaders used in automatic shoe machines which consists in forming a blank having the shrinkage of a casting and the spring of a last measurements incorporated therein, building a flange on the blank by winding a strip of material around the edge of a blank, and imparting a draft to the flange, substantially as described. 80

3. That improvement in the art of making casting patterns which consists in forming a suitable blank having the general shape of the desired casting, attaching paper thereto to shape the pattern to its finished form, and molding the paper to impart a draft to the pattern, substantially as described. 90

4. That improvement in the art of making patterns for casting the leaders used in automatic shoe machines which consists in mounting a sole on the bottom of a last, and projecting the edge of the sole upon a plane substantially as described. 100

5. That improvement in the art of making patterns for casting the leaders used in automatic shoe machines which consists in mounting a sole on the bottom of a last, projecting the edge of the sole upon a plane, and enlarging the area within the projections by the shrinkage of the metal used in the casting, substantially as described. 105

6. That improvement in the art of making patterns for casting the leaders used in automatic shoe machines, which consists in mounting a sole on the bottom of a last, projecting the edge of the sole upon a plane, enlarging the area within the projections by the shrinkage of the metal used in the casting to produce a blank, attaching a strip of material to the edge of the blank to form a flange thereon, and imparting a draft to the flange. 115

MARK E. FERNALD.
